UNITED STATES PATENT OFFICE.

STEPHEN H. EMMENS, OF LONDON, ENGLAND.

SHELL.

SPECIFICATION forming part of Letters Patent No. 414,389, dated November 5, 1889.

Application filed January 11, 1889. Serial No. 296,048. (No model.)

To all whom it may concern:

Be it known that I, STEPHEN HENRY EMMENS, a subject of the Queen of Great Britain and Ireland, and a resident of London, England, temporarily residing at Harrison, in the State of New York, have invented a new and useful Improvement in Artillery-Projectiles, of which the following is a specification.

This invention consists in certain novel features of construction and combinations of parts, hereinafter set forth and claimed, which are embodied in an improved explosive projectile for ordinary artillery.

The objects of the present invention are, first, to provide for using either a solid armor-penetrating head or a hollow fuse-inclosing head interchangeable therewith on one and the same shell-body, the latter containing an initial cartridge and a self-firing percussion-fuse; secondly, to provide the projectile with a self-firing percussion-fuse of superior simplicity; thirdly, to extend and lighten the base of the projectile so as to facilitate accurate centering, and by the same means to cushion the projectile against the first shock of discharge, and, fourthly, to adapt the improved base to the demands of breech-loaders.

Two sheets of drawings accompany this specification as part thereof.

Figure 1 of the drawings represents an axial longitudinal section of an improved armor-penetrating projectile for breech-loading artillery. Fig. 2 represents a front view of its armor-penetrating head. Fig. 3 represents a cross-section on the line 3-3, Fig. 1. Fig. 4 represents a rear view of its base, and Fig. 5 represents a small-scale full-length side view. Figs. 6 and 7, Sheet 2, represent sectional elevations of the head end or front of the projectile, showing interchangeable heads. Fig. 8 represents an elevation of the percussion-fuse enlarged one diameter. Figs. 9 and 10 represent longitudinal sections thereof on this scale, the latter illustrating its operation; and Fig. 9^x represents a sectional view similar to Fig. 9 of a modified fuse.

Like letters of reference indicate corresponding parts in the several figures.

Interchangeable heads A A², Figs. 1, 2, 5, 6, and 7, screw on the body B of this projectile by means of rearwardly-projecting lips C,

which are alike on both heads. Said head A is solid in front of the lip C, and constitutes a progressive punch adapted to penetrate armor with great efficiency, being of steel, cut in concentric flat-faced steps of successively-increased diameter toward the base, and suitably hardened. The alternative hollow head A², Fig. 7, has an axial bore D, and is provided with a time-fuse T, or a supplemental fuse of any approved description, confined to said bore. The body B is constructed with powder-chambers E², for a divided main charge separated by radial partitions F, Fig. 3, which are integral with the walls 65 of the body and with the metallic main portion of the base G of the projectile, and with a central tube H, Figs. 1, 3, 6, and 7. The base G extends rearwardly in the form of an internally-shouldered cylindrical wall 70 I, Figs. 1 and 4, stiffened by internal radial ribs J, and filled with wood packing K. The latter precludes the gases of the propelling-charge of the gun from bursting open the wall I, and acts as a cushion to receive the 75 first shock of the discharge. A suitable gas-check L occupies a circumferential groove in the wall I. The packing K is held in place by a washer M and bolt N, the latter screwing into the rear end of a central nipple O', 80 which constitutes the head of a base-plug O. This base-plug O screws tightly into an axial opening in the rear of the main diaphragm of the base G, and protrudes within the rear end of the tube H, where it carries a percus-sion-fuse P, attached thereto, so as to be inserted and held in place by means thereof.

The percussion-fuse P, Figs. 1, 8, 9, 9^x, and 10, comprises an outer metallic tube a, which is screwed on the reduced front end b of the 90 base-plug. Its front end is provided with a detonating-chamber c and with a hollow anvil-piece d, which extends rearwardly into the main chamber of the fuse, within a cap-primer e. A striker f, of conical outline in 95 front, is normally held at the rear end of said main chamber by the pressure of spring-fingers g. These fingers are attached within a hollow leaden cylinder h, which is in turn kept thereby in the front end of said main chamber, as shown in Figs 1 and 9, until the gun is fired, when the inertia of the cylinder

h causes it to slip backward on the point of the striker *f*, as represented by the arrow marked 1 in Fig. 9. The spring-fingers *g* then engage beneath a circumferential shoulder *i*, formed on said point, as represented in Fig. 10, and when the onward course of the projectile is arrested the striker, weighted by the leaden cylinder, flies forward, as represented by the arrow marked 2 in Fig. 10, and explodes the primer *e*, and thus fires the detonating-charge within the chamber *c*. The latter may preferably be formed by a flanged detonator *d*, inserted, open end inward, through a central opening in the front of the fuse, as represented in Figs. 1, 8, 9, and 10; or the chamber *c* may itself be filled with a suitable detonating composition, as represented in Fig. 9^x. A cartridge *E'*, of emmenseite or other high explosive, occupies the remainder of the tube *H* and constitutes an initial bursting or igniting charge to fire the main charge in the chambers *E'*. The bore *D*, Fig. 7, of the alternative head *A*² is aligned with said tube *H*, and the terminal detonator *v* of its fuse *T* is thus brought into direct communication with said cartridge *E'* when said alternative head is in use. In this case an annular gasket *U*, of leather or the like, covers the front ends of the powder-chambers *E'*. When the armor-penetrating head *A* is used, a circular gasket *V*, Figs. 1 and 6, is used. In either case suitable cushioning-wads *W*, of wood or the like, are fitted within both ends of each powder-chamber.

I do not claim herein the combination of a projectile-body provided with powder-chambers for a divided main charge separated by radial partitions integral with the walls of the body and with a central tube, and a head *A*², screwed on said body and having a bore aligned with said tube, and together with the latter accommodating an initial charge and a fuse or fuses for firing the same. This combination, formed by said alternative head *A*² and other features of the latter, and of the fuse *T* (represented in Fig. 7) are claimed in a companion specification of even date herewith, forming part of application, Serial No. 296,047, filed January 11, 1889. Neither do I claim, broadly, the combination, in an explosive projectile, of a percussion-fuse in an axial tube at rear and a time-fuse in front thereof, the latter separable from the former. Such a combination, broadly considered, is set forth in the expired patent of W. W. Hubbell, dated January 7, 1862, but without any provision for the use of interchangeable heads, which

distinguishes this part of my present invention.

Excepting the base *G*, as peculiarly adapted for breech-loaders by its cylindrical exterior and circumferential gas-check *L*, the several features of my present invention may be embodied alternatively in projectiles for muzzle-loaders, and other like modifications will suggest themselves to those skilled in the art.

Having thus described said improved projectile, I claim as my invention and desire to patent under this specification—

1. In a projectile for artillery, the combination, with a suitable head, of a cylindrical body removably screwed into the same, containing the main bursting-charge and having a central tube fast therein, which terminates substantially in line with the front of its walls, an initial charge within the front end of said tube, and a self-firing percussion-fuse located behind and which fires said initial charge, whereby the projectile is adapted for use with interchangeable heads, substantially as hereinbefore specified.

2. In a projectile for artillery, having a cylindrical body and an axial tube containing an initial bursting-charge, the combination, with a base-plug, of a self-firing percussion-fuse comprising an outer tube attached to said plug and having a detonating-chamber at its front end, a hollow anvil-piece projecting rearwardly into its main chamber, a primer embracing the extremities of the latter, a sliding striker having a conical front portion and a circumferential shoulder, and a hollow leaden cylinder having internal spring-fingers to engage behind said shoulder, substantially as hereinbefore specified.

3. A projectile for artillery, having a cylindrical hollow body and a rearwardly-extended base, the latter comprising an internally-braced outer metallic wall and wooden packing filling the same, substantially as hereinbefore specified.

4. A projectile for breech-loading artillery, having a cylindrical body and a rearwardly-extended base, the latter comprising an internally-braced outer wall which is cylindrical externally excepting a circumferential groove, and provided with a wooden packing within said wall and a gas-check within said groove, substantially as hereinbefore specified.
